[57] **CLAIM**

The ornamental design for a water level elevation measuring device, as shown and described.

DESCRIPTION

FIG. 1 is a perspective view showing my water level elevation measuring device design;

FIG. 2 is an enlarged fragmentary view of the center portion thereof showing the detail more clearly;

FIG. 3 is a top plan view thereof;

FIG. 4 is a bottom plan view thereof;

FIG. 5 is a rear elevational view thereof;

FIG. 6 is a left side elevational view thereof;

FIG. 7 is a front elevational view thereof; and,

FIG. 8 is a right side elevational view thereof.

In FIGS. 3 through 8 the flexible tubing shown in FIGS. 1 and 2 is omitted for clarity.

Portions of the water level elevation measuring device's scale have been eliminated for ease of illustration.

FIG. 1

FIG. 2

FIG. 3

FIG. 4

FIG. 5

FIG. 6

FIG. 7

FIG. 8
